WIRE KNOTTER

Albert R. J. Luke, Toronto, Ontario, Canada
Application August 8, 1952, Serial No. 303,556

2 Claims. (Cl. 140—115)

This invention pertains to wire knotters of the type used with hay balers or similar machines.

This application is a continuation-in-part of my prior application filed May 27, 1950, Serial No. 164,764, now abandoned, entitled Wire Knotter.

It is an object of this invention to provide a wire tying mechanism which will tie a knot in such a manner that it will not unwind regardless of the amount of tension under which the baled material is placed and at the same time utilize comparatively light gauge wire.

Another object of this invention is to provide a wire tying mechanism which will produce a knot in which a twisted portion is formed on either side of a main twisting pinion, the twisted portions so formed are each given an additional twist about an axis which is substantially 90° to the first twist by means of auxiliary pinions, the completed knots are then separated by a cutting means within the main pinion.

It is an object of this invention to provide a wire tying mechanism which will produce a knot that is first twisted on one axis and then twisted about a second axis which is substantially 90° to the first, thus forming a very tight knot, each leg of which is wound around the other.

Still another object of this invention is to provide a method for tying a wire knot in which, two strands of wire are twisted together at spaced locations along their length about one axis, the twisted portions so formed are given an additional twist about an axis which is substantially 90° from the first, the two knots so formed are separated by severing the two strands of wire between the knots.

Other objects and advantages will become apparent as this disclosure progresses. Accordingly the present invention may be considered as comprising the various constructions, combinations, or sub-combinations of parts as is hereinafter more fully set forth in the detailed description and in the claims, reference being had to the accompanying drawings in which:

Fig. 1 is a plan view of the bale before the knot is started showing the bale as positioned in the baling chamber.

Fig. 2 is a plan view of the bale after the needle arm has brought the wire across to the knotter from the opposite side of the bale.

Fig. 3 is a plan view of the bale after the knot is completed.

Fig. 4 is a plan view of the main twisted pinion showing one of the wires in position.

Fig. 5 is a plan view of the main twisting pinion with both wires in place.

Fig. 6 is a plan view of the main twisting pinion after it has made one complete revolution.

Fig. 7 is a plan view of the main twisting pinion after it has one and a half revolutions.

Fig. 8 is the same as Figure 7 but showing the two auxiliary twisting pinions.

Fig. 9 is an elevational view of the device as shown in Figure 8.

2

Fig. 10 is the completed knot.

Fig. 11 is a sectional view taken on line 11—11 of Figure 8 showing the cutter disc and spring.

Fig. 12 is an elevational view partially in section, 5 showing the knotter frame and driving means.

Fig. 13 is an elevational view partially in section, taken on line 13—13 of Figure 12.

Fig. 14 is a plan view in section taken on line 14—14 of Figure 12.

10 Fig. 15 is a sectional view of an auxiliary twisting pinion taken on line 15—15 of Figure 16.

Fig. 16 is a plan view in section taken on line 16—16 of Figure 14.

Referring more particularly to Figures 1, 2, and 3 15 the baling chamber 1 has two coils of wire 2, 2' located on opposite sides thereof. The knotter proper is located at one side of the chamber in the general area 3. The wire from the opposite side of the chamber is fed into the knotter by means of a needle arm (not shown) which is old in the art and is deemed to need 20 no further explanation here.

Figure 4 shows the main twisting pinion 4 in the position it ordinarily occupies while the bale is being formed, having the wire 5 from coil 2' lying in the 25 longitudinal groove 6 as the bale is formed in the chamber.

When the proper amount of hay is in the chamber, the main pinion 4 is caused to revolve one-half of a revolution, and needle arms (not shown) having a pair of spaced rollers on the end of the needle bring the wire 30 7 from coil 2 across the end of the bale 8 and place the wire in groove 9 of the pinion.

Main pinion 4 is then caused to make a complete revolution forming the wire as shown in Figures 7 and 8 into two twists 10 and 11.

The pinion 4 is of sufficient diameter so the 35 twisted portions formed thereby are of such length as to accommodate the auxiliary pinions 12, 13 which are presently to be described.

After the main pinion 4 has made one revolution, the two auxiliary pinions 12 and 13 are brought into their 40 respective concave recesses or slots 14 and 15 in pinion 4, the radial slots 24 and 25 of the auxiliary pinions fitting over the two twists 10 and 11 and then caused to rotate, thus forming knots 16 and 17.

It will be noted that the second twists imparted by the auxiliary 45 pinions 12, 13 are about an axis which is 90° to the common axis, i. e., the axis of main pinion 4, about which the first twists 10, 11 were formed.

In forming the second twists, the auxiliary pinions tightly wind each leg of the pairs of legs 10a—10b, 10c—10d, 11a—11b

50 and 11c—11d of the original twists 10, 11 respectively, about the other.

This twisting of each leg about the other offers considerable resistance to unwinding under tension.

By increasing the ratio of the diameter of gear 36 to the 55 diameter of segment gear 34', i. e., making gear 36 smaller or making segment gear 34' larger and consequently increasing the length of effective tooth area, main pinion 4 can be caused to rotate an additional revolution and thereby put an additional turn in the first twisted portions 10 and 11.

The knots 16 and 17 are separated as follows. A hardened disc 18 is rotatably-mounted in main pinion 4 which, as can be seen in Fig. 16, is made up of two half sections. Pin 19, which is fixedly mounted in the main pinion 4, 65 normally holds the disc 18 in its inoperative position against the pressure of the spring 20. When it is desired to separate the knots, the dog 21 acts on notch 22 of the disc 18 causing the disc to rotate through a small arch thus severing the wires by the action of the hardened disc jaws 23 against the hardened jaws formed by the grooves 6 and 9 of the pinion. Thus two knots are 70 formed, one on the bale just completed and the other,

shown at the lower left hand corner of the bale in Fig. 1, fastens the two wires together to form the beginning of the next bale loop. Thus there are two knots formed for each loop but only one operation of the knotter is required per loop. All of the wire is utilized and there are no free ends or particles of wire left in the bale or in the field.

The operation of the knotter for a complete cycle is as follows. This knotter ties two knots at the same time (two loops per bale) and as the mechanism is identical in structure and operation for both the upper and lower knotter, reference will be made to one or the other in this description with the understanding that they are identical.

While the bale is being formed, wires from coils 2 and 2' mounted on the baler frame are lying in grooves 30, 15 30' (Figure 13). They are pulled along until the trip (not shown), which is operated by a metering wheel well known in the art, put the mechanism into operation.

In Fig. 12, the shaft 32, which is rotatably mounted in the knotter frame 33, is caused to turn by the trip mechanism through a bevel gear (not shown) at the top of the shaft. Secured to the shaft 32 are two segment gears 34 and 34' which drive pinion 36 and the corresponding pinion (not shown) for the top knotter. Mounted on the same shaft 38 as pinion 36 is the gear 40 and for each cycle of the knotter they make one revolution as does shaft 32. The main pinion 4 is turned 1½ revolutions by gear 40 for each cycle as previously described, causing the twist in the wire as shown by Figure 7. At this time the main pinion 4 stops turning due to the dwell portion of the segment gear 34.

The means for swinging the auxiliary pinions 12 and 13 into working position and rotating them will now be described. Secured to the drive shaft 32 (Figure 12) is a bevel gear 42, which drives through bevel gear 44, shaft 46, bevel gear 48, and bevel gear 50 to rotate the cam shaft 52 (Figure 14) which is secured to bevel gear 50 and rotatably mounted in the knotter frame members 54 and 56. During the entire knotting cycle, the cam shaft is continually rotated and the cams 58 and 60 are so designed that they are inoperative until the main pinion 4 stops turning. In Figure 16 is shown the lower auxiliary twisting pinions 24, 25 in the open position and the top ones 12, 13 in the closed position for the sake of illustration. In practice, however, they could all twist at the same time and it would be impossible for the arms 62, 63, 64 and 65 to assume the position shown in Figure 16 as arms 62 and 63 are of one piece and diagonally opposite each other and both are in the closed (or open) position at the same time. The same is true of arms 64 and 65. The cam 58 bears against the roller 67 of the pair of arms 64, 65 and the cam 60 (Figure 13) bears against the roller 69 of arms 62, 63, thus forcing the auxiliary gears in and out of working position. When in the operative position, the grooves 24 and 25 of the auxiliary pinions straddle the twist 19 and 11 in the wire at either side of main pinion 4.

At this time, segment gear 71 (Figure 14) starts to turn gear 73 which is rotatably mounted on shaft 75. The auxiliary twisting pinions 12, 13 are driven by gear 73 through idler gears 77 (Figure 16) which are rotatably mounted on arms 62, 63, 64 and 65 and are in constant mesh with the auxiliary pinions 12, 13 and the gear 73. Auxiliary pinions 12 and 13 make two revolutions per cycle and produce the knot shown in Figure 10.

The cutting disc 18 previously described is operated as follows. Mounted on the lower portion 80 of gear 73 are two segment cams 82 (Figures 12 and 13) which push on rollers 84 which are rotatably mounted in dogs 21. After the auxiliary pinions have been rotated to produce the finished knot, the cams 82 push this dog 21 into contact with the notch 22 in the disc 18 and rotates it enough to shear the wires. The spring 20 then returns the disc to the non-operative position. The wires are thus freed from the knotter which is then in position to start through another cycle when actuated by the metering wheel and trip previously mentioned.

Having thus shown and described my invention, I claim:

1. In a wire knotter a common frame member, a main twisting pinion rotatably mounted on said member and having two diametrically opposed radial slots for receiving two sections of wire, gear means rotatably mounted on said frame member for rotating said main pinion thus forming a twisted portion at either side of said main pinion, auxiliary twisting pinions shiftably mounted on said frame member each having a radial slot to straddle the said twisted portions at either side of said main pinion, arm means swingably mounted on said frame to swing said auxiliary pinions into a position to straddle said twisted portions and return them to an inoperative position, gear means rotatably mounted on said frame to rotate said auxiliary pinions while they are in the operative position, a cutting disc rotatably mounted in said main pinion and having radial slots cooperating with said slots of the main pinion to sever the wires, means mounted on said frame to rotate said cutting disc after said auxiliary pinions have been rotated.

2. In a wire knotter, a common frame member, a main twisting pinion rotatably mounted therein and having two diametrically opposed radial slots for receiving two sections of wire, gear means rotatably mounted in said frame for rotating said main pinion and thereby forming a twisted portion at either side of said main pinion, auxiliary pinions swingably mounted on said frame and having a radial slot adapted to straddle said twisted portions, arm means swingably mounted on said frame member to swing said auxiliary pinions in and out of operative position, gear means rotatably mounted on said frame member to rotate said auxiliary pinions while in the operative position, a cutting disc rotatably mounted in said main pinion having two radial slots for cooperating with said radial slots of said main pinion, means mounted on said frame for rotating said disc to sever the wires after said auxiliary pinions have been rotated.
